SPINNING REEL

Carl J. Velte, Jr., Grand Rapids, Mich., assignor to
Shakespeare Company, Kalamazoo, Mich., a corpora-
tion of Michigan

Filed Dec. 17, 1963, Ser. No. 77,830

Term of patent 14 years

(Cl. D31—4)

FIG. 1 is a top plan view of a spinning reel showing my new design;

FIG. 2 is an elevation as seen from the left of FIG. 1;

FIG. 3 is a fragmentary rear elevation taken in the direction of line 3—3 of FIG. 2;

FIG. 4 is a front elevation thereof;

FIG. 5 is a rear elevation thereof;

FIG. 6 is an elevation as seen from the right of FIG. 1; and

FIG. 7 is a sectional view taken on line 7—7 of FIG. 6.

The essential features of the design reside in the portion shown in solid lines.

I claim:

The ornamental design for a spinning reel, substantially as shown and described.
